UNITED STATES PATENT OFFICE

JOSEPH A. MARTOCELLO, OF PHILADELPHIA, PENNSYLVANIA

SUPPORT FOR DROP TUBES

Application filed October 1, 1927. Serial No. 223,452.

My invention relates to supports for drop tubes for use in raw water ice manufacture.

One of the purposes of my invention is to provide air tube supports from a lateral located above ice cans by brackets in which the lateral can be tilted to remove the brackets from beneath the air tubes, and to then remove the lateral and the brackets from their positions over the cans.

10 A further purpose is to protect an air lateral outlet for supplying a drop tube by a bracket secured to the lateral and by which the tube is supported.

A further purpose is to support an air tube 15 from a bracket by spaced bracket terminals from which the tube and bracket can be withdrawn one relatively with respect to the other by movement of either in a direction generally transverse to the tube.

20 A further purpose is to provide an air lateral for a can basket with taps at intervals, to support the drop tubes by brackets located at the taps and straddling the taps so as to protect them and to pass the connecting flexible tubes from the taps to the tubes through the brackets thereby giving maximum protection for the tube and tap connection and minimum length of connection. The entire path desirably slopes downwardly preventing 25 trapping of condensed moisture.

A further purpose is to provide a lateral 30 for use with a can basket with brackets, one for each individual can, having forked bracket ends to facilitate separation of the brackets and tubes.

A further purpose is to provide bracket supports for air tubes permitting free swinging in two separate planes and thereby permitting swinging in any plane or in a path 35 not confined to any plane.

A further purpose is to support a drop tube 40 terminal from prongs on opposite sides of the tube so as to give the tube tilting or sliding movement parallel with the length of the prongs and tilting or sliding movement transversely to the length of the prongs, selecting the movement desired preferably according to the contact intended with the surface of the prongs.

50 A further purpose is to provide parallel

nearly horizontal supports for a tube terminal, which latter may be of horizontal or sloping flat or curved contour parallel with the supports and also of any of these contours transversely to the supports, according to 55 whether rocking, rolling or sliding connection between the horizontal supports and terminal be desired. The supports may have bearing against the terminal upon their inner (nearer) edges or upon their outer (farther) 60 edges or between them and may be curved in transversed section to cooperate with any contour of the tube terminal according to the whim or need of the designer.

A further purpose is to provide drop tube 65 support from a lateral by a bracket having spaced horizontal walls for tube terminal support, permitting the tube to be supported in different positions nearer to or further from the lateral so as to accommodate differences in flexible tube air connections between the lateral and aerating tube.

A further purpose is to support a tube terminal upon lugs rolling or rocking upon substantially horizontal surfaces on opposite 75 sides of the tube and adapted to perform their rolling or rocking function equally well at variant distances along the lengths of the prongs so as to cooperate with different lengths of air hose connecting between the 80 air tube and the lateral. Transversely of the prongs the terminal can slide or rock as preferred.

A further purpose is to provide for rolling 85 of aerating tube supporting lugs within seats in prongs on opposite sides of the tubes having seat curvatures of slightly greater radii than the radii of curvature of the lugs, the tubes swinging transversely to the lengths of the prongs by sliding or tilting as preferred.

A further purpose is to locate the flexible 90 tube connection with the nipple for drop tube engagement as low as possible.

My invention relates both to processes involved and to apparatus by which the processes may be carried out.

I have preferred to illustrate my invention by a few forms only among a considerable number in which my invention may be displayed, selecting forms which are practical,

efficient, reliable, convenient and inexpensive and which at the same time well illustrate the principles involved.

Figure 1 is a fragmentary top plan view of a header and can basket with which the header is associated.

Figure 2 is a section upon line 2—2 of Figure 1.

Figure 2a is a broken section of Figure 1 taken upon line 2a—2a and showing a fragment only of the surrounding structure.

Figure 3 is an enlarged section of Figure 1 taken upon line 3—3.

Figure 4 is a section of Figure 3 taken upon line 4—4.

Figure 5 is a fragmentary top plan view of a portion of Figure 3, the tube and hose connection being removed.

Figure 6 is an enlarged perspective of a single bracket such as is shown in Figure 3.

Figure 7 is a fragmentary perspective on line 7—7 of Figure 6.

Figure 8 is a perspective and Figure 9 is a section upon line 9—9 thereof showing one of the tube terminals involving my invention.

Figure 8a is a perspective similar to Figure 8, but of a modified form.

Figures 10, 10a, 12, 12a, 15 and 18 are fragmentary side elevations showing different forms of brackets and tube terminals in position for use.

Figures 11, 13, 16 and 19 are sections upon lines 11—11, 13—13, 16—16 and 19—19 of Figures 10, 12, 14 and 18, respectively.

Figure 14 is a top plan view of the construction seen in Figure 15.

Figures 17 and 19 are sections corresponding in position to line 16—16 of Figure 14 but showing different forms of the invention.

In the drawings similar numerals indicate like parts.

Though various parts of my invention are applicable for the support of aerating tubes in the individual cans as distinguished from cans located in can baskets, the features relating to the release of the tubes from their supporting brackets by tipping of the lateral are most useful in can basket construction, where the release permits bodily removal of the lateral and all of the brackets together. The first part of my invention correspondingly will be described in connection with the can baskets.

In Figures 1 and 2 I have shown can basket structure in which the cans 22 are mounted between rails or bars 23 in such position as to be capable of being handled as a unit. The basket is lifted by means of a crane and the cans are all emptied at one time. Structure of this general character is so well known that it will not be necessary to illustrate or describe in detail the arrangement by which the rigid mounting of the cans in the basket is secured to permit unit handling.

Whatever the can basket construction it

is quite desirable that the lateral 24 shall be so mounted that it will permit the cans of ice to be emptied from the cans or that the lateral can be thrown out of the path of the ice as it is emptied from the cans.

Ordinarily the lateral will, of course, be of the usual piping; but my invention is intended to apply equally well where laterals of non-circular section are used because of convenience or security of clamp engagement. The lateral is rested upon the upper surface of the cans or of the basket and preferably rests within recesses 25 in the transverse basket plates 26, in order to fix the position of the lateral so as to center its brackets in the cans and to limit side movement of the lateral when the lateral is tilted for purposes of bracket disconnection from the drop tubes.

The lateral 24 is retained against normal swinging movement by an arm 27 which may be temporarily connected as by a pin 28.

The lateral is connected with the header 29 temporarily during use by a flexible connection 30, which is stretched over the end of the lateral hose coupling at one end and over a nipple 31 at the opposite end. The nipple 31 is inserted within an automatic valve 32 which is secured in the header 29, so that connection of the nipple opens the valve and disconnection allows the valve to close. Such valves are old in the art.

The preferred form of bracket 33 is shown in Figures 1, 3, 4 and 6 and is of skeleton form so as to give considerable width of bracket, longitudinal of the lateral and great stiffness for the amount of weight involved. It also affords protection for the air connection.

The bracket as shown, comprises a lateral-encircling band 34 continuous throughout its width at the top 35 and at the lower front portion 36 but cut away along the end and rear part as at 37. This allows access through the bracket for insertion within the lateral of the outlet nipple 38. Connection is made between it and the drop tube 39 through flexible tube 40 and nipple 38'. This nipple fits into the tapered opening 41 within tube terminal 42. The terminal is provided with the usual thawing needle guide 43 and with some type of lug 44 or flange support 45.

The encircling member is stiffened by ribs 46 and is kerfed at 47 to form a clamp adapted to be set in desired angular and longitudinal position, with respect to the lateral, by means of bolts 48 passing through openings 49 and 49'.

The bracket arm is stiffened by side ribs or flanges 50 and is open at 51 both to lighten the arm and to allow the air connection to pass through it, as seen best in Figures 3 and 4.

Near the outer end the bracket is stiffened by a transverse rib 52 and is bifurcated to provide supporting fingers or prongs 53.

In freezing raw water in cans for the pur-

pose of making commercial ice, the ice forms on the outer part of the intended cake first, closing in progressively toward the center of the cake. Though the thickness of the layer thus formed is not uniform throughout the cake, this results in the raw water space being progressively reduced in length (i. e., along the longer dimension in horizontal sections) and width, but up to the time of final freezing of the core always presenting a section much longer along the length of the can than across the can.

In the methods of aeration heretofore in use, effort has erroneously been made to confine the swinging of the aerating tube or drop tube to swinging across the can, wholly overlooking the fact that the sides of the entire unfrozen section require agitation to assist in throwing off impurities from accumulating ice and that the transverse swinging movement formerly provided confines the direct agitation to the sides of the middle portion only, ignoring the needs of those parts of the sides which are furthest removed from the center.

My invention is intended to provide for swinging of the tube to reach and aerate those portions of the sides which are further from the center by a movement lengthwise of the unfrozen cross section, and at the same time to get intimate agitation at the sides of the open portion at intervals by given the ends of the tube an irregular movement which approximates an ellipse.

I thus avoid the error of restricting swinging movement of the tube to a plane, yet perfectly provide for the greater extent of swinging movement longitudinally of the unfrozen cross section as compared with the movement provided transversely of this cross section.

By balancing the restraining effect of the connecting rubber hose against swinging movement in one direction as compared with swinging in a direction at right angles thereto, against a greater restraining effect of the tube terminal support upon the bracket in the latter direction of movement as compared with the former direction, I am able to control the path of movement fully. I provide a variety of means of support which permit a great deal of adjustment of comparative restraint in different directions due to tube support. I thus furnish the elements by which the designer may attain substantial elliptical movement having different proportions of ellipse varying up to approximately circular tube movement.

The separated or spaced terminal prongs or supports are shown in several different shapes to cooperate with different types of supporting lugs or flanges upon the terminals of the aerating (drop) tubes, with the purpose and intent of favoring different paths of movement of the tube.

One feature of my drop tube support from the bracket is independent of the type of oval movement or circular movement of the tube. This concerns the extension of the supporting edge or surface on each of the prongs to form approximately horizontal edges or ledges upon which the tube terminal may rest at any point along the length of the prongs, accommodating to different lengths of flexible tube 39, so that with an approximately correct tube length at the start, the tube supporting lugs, flange or collar will adjust itself to that position longitudinally of the edges or ledges at which there is least resilient-tube-flexing resistance to the free swinging of the drop tube. This feature is present in all of the forms of my invention except that shown in Figures 18 and 19.

At the start of the discussion regarding these tube supports and the flexure of the resilient tube 39 due to the swinging of the aerating tube, it will be evident that, taking our directions from Figure 3 in order to simplify the discussion, there will be ordinarily more resistance from the flexure of tubing 39 by swinging of the aerating tube when the swinging takes place parallel to the paper and hence varies the distance between the nipples 38 and 39, kinking tubing 40, than when the swinging of the tube takes place in a plane through it perpendicular to the paper, bringing torsion and side swaying strains upon the tubing 39. For this reason, if the aerating tube is to swing with equal freedom in all directions, the support of the terminal within the bracket prongs should ordinarily provide less resistance to swinging within planes parallel to the paper (parallel to the lengths of the prongs) than to swinging in planes perpendicular to the paper (transverse to the lengths of the prongs), so that the sums of the two resistances met (in distortion of tube 39 and in rocking or swinging the tube upon the bracket prongs) will be somewhat evened up and equalized in this way. With this as a starting point, these factors can be properly appraised to give the exact proportion desired between the longitudinal and side movements of the tube.

In order to equalize the resistances I have made the resistance at the prongs to swinging in planes transverse to the prongs slightly greater in most of my forms than the resistance at the prongs to swinging parallel with the length of the prongs. I have provided a variety of types of supports at the prongs in order that the user of my invention may have a selection of types to facilitate apportionment of the resistance to swinging of the tube in different directions, thus making it possible to secure approximately any shape of ellipse desired.

With all of my forms also it is desirable to be able to disconnect the nipple 38' from the tube by twisting movement and for this

purpose I provide resistance against undue turning movement of the tube by engagement of a non-circular terminal section such as the rectangular portion 54 with the sides of the 5 prongs as at 55 and 56. The sides 56 should not approach the tube terminal sufficiently to interfere with the swinging path desired.

It will be noted that after the tubes are frozen in position in the can of ice and the 10 nipple 38' have been released from the tubes, the lateral can be swung in a clockwise direction (Figure 3) by release of the holding pin and lifting the restraining arm so as to permit lifting of the lateral and the brackets 15 bodily from the can to remove the lateral and brackets wholly from the path of emptying movement of the ice when passing out from the cans. This feature, though of greatest utility in can basket practice, is of value 20 also in operation of individual cans using laterals which are located over the cans in use. The types of supports of the aerating tubes from the brackets which I have shown are available both in can basket use and with 25 individual cans located in permanent can-receiving frames.

In the form of brackets illustrated in Figures 3, 4, 5 and 6 the ledges 57 are horizontal and present plain upper surfaces. These 30 ledges will support a variety of lugs or flanges, giving flat support to lugs 44 of Figures 8 and 9 in which the lugs have flat under faces 58, and edge support only where the under lug surfaces curve or slope outwardly 35 and upwardly and the ledge is not correspondingly curved or sloped.

The flat-bottomed horizontal lugs 44 shown in Figures 8 and 9 slide freely to whatever point may best suit the length of hose 40 between the limits of the horizontal ledges. They rock parallel with the prongs upon lug edges 59 and transversely to the prongs upon edges 60. The selection of position is automatic and it will be noted that 45 the lugs rock equally well at any position between the limits or at the limits, lifting the tubes slightly in each case and rocking more easily upon edges 59 than upon edges 60. Most of the time the rocking will be a composite of the two, lifting upon and about 50 corners of the lugs.

The width of the lugs as well as the distance between the ends of the lug upon which they rock can be altered in the design so as 55 to secure any proportion desired between the radii about which rocking takes place so as to make the additional energy required to rock about the longer radius offset any proportion or all of the additional energy required 60 in flexing the rubber tube 39 to swing the tube in planes parallel with the length of the bracket, thus securing equality in the energy required to swing in these different planes or any approach to it which is desired. 65

In the form shown in Figure 8a the same tilting action about edges 59 takes place with lifting of the tube in each case as in the form shown in Figures 8 and 9, but the curved under surfaces of the lugs ensure rocking in the other plane about the inner edges 61 of the bracket unless the curvature be steep enough to make the lugs slide. 70

As will be seen, the form of Figure 8a reduces the tilting resistance where tilting takes place, and reduces the resistance below that of tilting where the tube terminal slides upon the inner edges of the bracket, so as in any event to make the resistance to movement transverse to the bracket less than in the form shown in the Figures 8 and 9. 75

In the form shown in Figures 10 and 11, the resistance offered by the support of the tube terminal upon the bracket to swinging movement transverse to the bracket length is substantially the same as in Figure 8a, providing tilting upon a relatively small radius where the slope of the edge of lug 41' is gradual, or sliding movement upon the edge where the slope is considerable. However, against 80 swinging movement along the length of the bracket the resistance offered by the movement of the tube terminal upon the bracket is very much reduced as compared with that offered by the tilting flat-bottomed form of 85 Figures 8, 9 and 8a to the movement in this direction, and is much reduced as compared with the tilting movement transverse the length of the bracket or the sliding movement in the same direction in Figures 8a, 10 and 100 11. This is accomplished by curving the undersides of the lugs 41' in Figures 10 and 11, so that these lugs roll upon the edges 57 of ledges 51 in the central position shown in Figure 11, or tilt but slightly in positions variant from that in Figure 11. It will be 105 noted that they roll equally well upon any part of the horizontal ledges with which they engage.

The form shown in 10a rolls well even though it engages the entire ledges and not edges only. The difference between Figures 10 and 11 and 10a is therefore immaterial as regards this rolling friction along whatever part of the ledge is engaged by the lugs, but the difference in tilting in the opposite direction transverse to the bracket length is quite material since in Figure 10a the aerating tube would swing by rocking upon the outer edges of the supports, involving lifting of the tube upon a relatively long radius at each swinging movement. 110

The form shown in Figures 12 and 13 is quite comparable with that shown in Figures 10 and 11, except that swinging transversely to the length of the prongs where it involves tilting of the tube about either lug as a center, has a longer radius for this tilting (about outer edges 62) than in Figure 11, and swinging in a direction parallel 115 120 125 130

with the lengths of the prongs requires slight tilting of the tube upon the edges 592 of the lugs because the greater spacing of the bracket edges upon which the tube terminal rests results in this engagement with the tube terminal taking place upon the flattened outer ends of the lugs instead of upon the rounded inner portion of the lugs with which engagement is made in Figures 10 and 11.

5 In Figure 12a the lug is shown as curved upon the underside all the way out and therefore as rolling at a point of small diameter upon the surface of the bracket ledge.

In the form shown in Figures 14, 15 and 16 the surface of the prongs are curved cylindrically at 63 so as to cooperate with the spherical under surface 45 of the tube terminal, permitting sliding movement of the terminal in its cylindrical side supports 20 when the tube swings transversely of the prong lengths and providing for rolling movement of the spherical surface of the terminal upon the cylindrical surface of the bracket prong support when swinging takes 25 place in the plane of the length of the bracket. Figure 17 is closely similar to Figure 16, differing in that there is a convex ledge surface 64 at each side to cooperate with the spherical tube terminal. This makes little 30 difference, except to substitute line contact for the more full engagement of the spherical under surface with the cylindrical surface in Figures 14-16.

In all of the forms thus far described a 35 horizontal ledge surface is provided at each of the prong supports, so that the tube terminal can be placed in a position conveniently to cooperate with the length of the rubber hose provided, automatically taking the best 40 position for the purpose if it be placed in what would prove a strained position.

In the forms shown in Figures 18 and 19, however, the prongs are not provided with 45 horizontal surfaces giving a range of position for the tube terminal lugs, but are formed with transversely straight curved upper surfaces 65 of slightly larger concave radii than the radii of the convex curve 66 of the lugs. The curvature is such that the lugs 50 can roll in their seats to the extent desired while resting upon absolutely flat bottoms. The engagement of the lugs with the width of the supporting bracket ledges results in 55 swinging movement transverse to the length of the bracket tilting the tube about the ends of the lugs.

I have thus shown the various elements entering into tube terminal support by prongs to proportion the resistance to swinging movements parallel with and across the lengths of the prongs in any manner desired, and to secure the several movements by sliding or rolling or tilting, as preferred.

60 65 There are of course many more combinations

of these elements and methods of mounting and swinging which I cannot attempt to discuss at full length.

In operation, the brackets are placed upon the lateral before the nipples 35 are inserted within the lateral. The nipples are then inserted and the rubber tubes are put in place with nipples 37 in position for engagement with the tapered top openings in the aerating tubes. The tubes are then placed in position, being inserted from the ends of the prongs and the tapered nipples are inserted within the tubes. The air is thus supplied to the tubes and results in more or less irregular movement of the tubes both longitudinally 70 of the can cross section and transversely of this cross section, the proportions of these several movements which enter into the contour of movement of the tube varying largely with the relative ease of movement in the 75 planes parallel with and across the lengths of the prongs. This proportion is determined by the combined resistance to swinging movement due to engagement of nipples 38 with the flexible tubes and the resistance 80 offered by the tilting, rolling or sliding of the tube terminals upon the surfaces of the 85 bracket prongs.

I preferably thus secure travel of the air discharging tube end of the can sufficient to 90 scour all parts of the ice surface which is being formed, along with lateral movement of the tube toward and from the longer walls of ice sufficient to make the scouring effective 95 all along the line, as distinguished from limiting the scouring to that portion of the longer walls lying in the approximate center of the can.

Obviously these forms are all broadly the 100 same invention.

It will be obvious that those skilled in the art will, in view of my disclosure, see various other modifications and changes which may be made in my structure to secure the benefit of all or part of the invention without copying the forms shown; and it is my purpose to include herein all such as come within the reasonable spirit and scope of my invention.

Having thus described my invention what I claim as new and desire to secure by Letters Patent is:

1. An ice can basket containing ice cans, a lateral carried by the basket, means for preventing the lateral from rotating on its own axis in normal operation, a release therefor 110 to permit rotation on its own axis when desired, drop tubes one in each can and brackets supporting the drop tubes and mounted upon and adjustable longitudinally about the lateral whereby all of the brackets may be 115 swung together by turning the lateral when the lateral is released.

2. An ice can basket containing ice cans, a lateral carried by the basket and secured thereto, means for preventing the lateral from 120

130

rotating on its own axis in normal operation, brackets secured to the lateral extending downwardly and away from the lateral, and aerating tubes supported from the brackets and free to move relatively to the brackets 5 upwardly and away from the lateral, permitting release and rotational swinging of the lateral to withdraw the brackets downwardly and away from the tubes so as to permit removal of the lateral and the brackets from above the cans.

3. A plurality of ice cans, a lateral supported in proximity to the tops of the cans and releasably restrained from rotation with 15 respect to them, brackets carried by the lateral and having open ends for seating and suspending aerating tubes, permitting their removal through the open ends, and a plurality of tubes, one suspended by each 20 bracket, whereby downward movement of the open ends by angular movement of the lateral permits withdrawal of the lateral and the brackets from the tubes and from the cans.

4. An ice can basket containing cans and 25 having frame members recessed to receive a lateral, a lateral resting in the recesses, a rigidly mounted clamp for the lateral releasably restraining the latter from rotating 30 about its own axis at will, aerating tubes for the cans, and bracket supports for the tubes mounted upon the lateral holding the tubes in normal position of the lateral, and removable by downward and rearward swinging 35 of the brackets through partial rotation of the lateral.

5. An air lateral, a drop tube, an air connection with the lateral, a nipple terminating the air connection and engaging the tube, 40 and a bracket supporting the tube and straddling the air connection at the lateral to protect the connection by the side walls of the bracket.

6. In a raw water ice system, a drop tube, 45 an air lateral, an air connection tapped to the lateral and a bracket surrounding the lateral, recessed at the air connection to straddle the air connection and again recessed to permit the air connection to again 50 pass through the bracket, and having a drop tube support at the end of the bracket in position for the tube supported therein to be engaged by the air connection.

7. In a raw water ice system, an air lateral, 55 a bracket supported from the air lateral, an air connection with the lateral terminating in a flexible tube, a nipple carried by the tube, a drop tube, a drop tube terminal and a bracket end having spaced supports for the air tube terminal, the supports extending 60 generally lengthwise of the bracket to permit the air terminal to engage the bracket in varying positions along the length of the bracket according to the length of the flexible tube in the air connection.

8. In a raw water ice system, an air lateral, a bracket supported from the air lateral, an air connection with the lateral terminating in a flexible tube, a nipple carried by the tube, a drop tube engaged by the nipple and having an upper supporting terminal, loosely free to rock on the bracket lengthwise and transversely of the bracket and a bracket end supporting the terminal and having greater resistance to swinging movement of the tube 75 in a plane parallel with the length of the bracket end as compared with that in a plane transverse to the length of the bracket end.

9. In a raw water ice system, an air lateral, a bracket supported from the air lateral, an air connection with the lateral terminating in a flexible tube, a nipple carried by the tube, a drop tube engaged by the nipple and having an upper supporting terminal, and a forked bracket end supporting the terminal, 80 rocking on it and having less resistance offered by the engagement of the bracket with the tube terminal to swinging of the tube in a plane parallel with the length of the bracket end than in a plane transverse to the length 85 of the bracket end.

10. In a raw water ice system, an air lateral, a bracket supported from the air lateral and ending in a forked tube support, an air connection with the lateral terminating in a 90 flexible tube, a nipple carried by the tube, a drop tube engaged by the nipple and having tilting engagement with the bracket, with swinging movement of the tube transverse to the portions of the bracket upon which the tube terminal rests, whereby the tube is lifted with each swinging movement of the tube, and having more resistance to swinging movement in planes transverse than in 95 those parallel to the length of the bracket end.

11. In a raw water ice system, an air lateral, a bracket supported from the air lateral, an air connection with the lateral terminating in a flexible tube, a nipple carried by the tube, a drop tube engaged by the nipple and having an upper supporting terminal and a bracket end cooperating with the terminal and having line engagement between the bracket and terminal along the inside of the bracket walls.

12. In a raw water ice system, a plurality of drop tubes, an air lateral supplying the drop tubes, adjustable angularly about its own axis, and fastening normally to hold the lateral in position to support the tubes, air connections from the lateral to the tubes and plurality of brackets mounted upon the lateral and adapted each to support one drop tube whereby the lateral may be turned to lower the brackets from engagement with 120 the tubes.

13. In a raw water ice system, a plurality of drop tubes, a lateral supplying the drop tubes, adjustable angularly about its own axis, and fastening normally to hold the 125

lateral in position to support the tubes, air connections from the lateral to the tubes and a plurality of brackets adjustable circumferentially about the lateral mounted upon the lateral, downwardly sloping and adapted each to support one drop tube whereby the lateral may be turned to lower the brackets from engagement with the tubes.

14. In a raw water ice system, a drop tube bracket having a forked supporting end provided with horizontal ledges on opposite sides of the drop tube position, a drop tube and a drop tube terminal having lugs bearing on the ledges and flat on their under sides the length of the ledges being longer than the flat undersides of the lugs to permit movement of the lugs longitudinally of the ledges.

15. In a raw water ice system, a drop tube bracket having a forked supporting end provided with ledges on opposite sides of the drop tube position, the ledges providing a horizontal support and a drop tube support in normal use movable longitudinally of the ledges.

16. In a raw ice water system, a drop tube bracket having a forked supporting end provided with ledges on opposite sides of the drop tube position, an air tube, and an air tube terminal fitting therein, the terminal being of non-circular section below the support to engage adjoining parts of the fork of the bracket and prevent undue turning of the tube.

35 17. In a raw water ice system, a plurality of cans placed side to side, an air lateral across the cans in proximity to the tops of the cans and near the center of one half of the width of the cans, a plurality of downwardly sloping brackets adjustably secured to the lateral, one for each can and drop tubes, one in the center of each can supported by the brackets and air connected with the lateral.

45 18. The process of equalizing the restraint against swinging movement of an aerating tube having connection with a flexible air supply tube at one end and support upon a bracket, which consists in supplying resistance to swinging movement in different directions at the bracket support reversely proportional to the resistance to swinging movement offered by the supply tubing connection.

55 19. The process of supporting a tube terminal having projecting surfaces from a bracket having side bars on opposite sides of the tube terminal, which consists in providing tilting of the tube support upon the side bars at different radii in one plane as compared with a plane transversely thereto to offset differences in resistance to tilting due to conditions in other parts of the connection.

65 20. In a raw water ice system, a drop tube

bracket having a forked supporting end provided with ledges on opposite sides of the drop tube position, means for supporting the bracket, a drop tube and a terminal for the drop tube carrying lugs curved on their undersides and adapted to bear on the ledges, whereby the tube rolls on the lugs in one direction and tilts upon one of the lugs in a direction transverse thereto.

21. In a raw water ice system, a drop tube bracket having a forked supporting end provided with ledges on opposite sides of the drop tube position, a support for the bracket, a drop tube and a drop tube terminal of convex contour sloping upwardly from the tube whereby the terminal slides on the ledges in one direction of movement and rocks upon both of the ledges in a direction of movement transverse thereto.
